UNITED STATES PATENT OFFICE.

CLARENCE A. ROSS, OF JOLIET, ILLINOIS, ASSIGNOR OF ONE-HALF TO WILLIAM F. HORSTING, OF CHICAGO, ILLINOIS.

MACHINE FOR MEASURING AND VENDING LIQUIDS.

Application filed September 10, 1921. Serial No. 499,598.

To all whom it may concern:

Be it known that I, CLARENCE A. Ross, a citizen of the United States, and a resident of the city of Joliet, in the county of Will and State of Illinois, have invented certain new and useful Improvements in a Machine for Measuring and Vending Liquids; and I do hereby declare that the following is a full, clear, and exact description of the same, reference being had to the accompanying drawings, and to the numerals of reference marked thereon, which form a part of this specification.

This invention relates to pumps of the sort which are used in dispensing gasoline for automobiles.

It is an object of this invention to combine with such a pump a device which shall punch, cut off and deliver a ticket from a roll of tickets so that the amount of gasoline delivered shall be indicated by the punch mark on the ticket.

It is a further object of this invention to interlock a pump operating mechanism and a ticket delivering mechanism so that a ticket cannot be punched and delivered unless gasoline is actually pumped.

It is further an object of my invention to provide means for causing the ticket to travel past the punching mechanism by the motion of the pump operating mechanism and means for causing the ticket to be punched, severed from the strip of tickets and delivered from the machine by the motion of an auxiliary handle.

Other and further important objects of this invention will be apparent from the disclosures in the drawings and specification.

The invention (in a preferred form) is illustrated in the drawings and hereinafter more fully described.

On the drawings:

Figure 1 is a front view and Figure 2 a side view of a gasoline pump to which my invention is applied.

Figure 3 is a section upon the line 3—3 of Figure 1.

Figure 4 is a vertical section through the ticket delivery mechanism.

Figure 5 is a horizontal section upon the line 5—5 of Figure 4.

Figure 6 is a detail section upon the line 6—6 of Figure 5.

Figure 7 is a detail section of the longitudinal shaft and the members mounted thereon.

Figure 8 is a vertical section upon the line 8—8 of Figure 4.

Figure 9 is a central vertical section of the device taken upon the line 9—9 of Figure 10.

Figure 10 is a vertical section taken upon the line 10—10 of Figure 9.

Figure 11 is a detail section taken upon the line 11—11 of Figure 5.

Figure 12 is a detail section taken upon the line 12—12 of Figure 4.

Figure 13 is a section showing the plates which constitute the guideway for the tickets. It is taken upon the line 13—13 of Figure 10.

Figure 14 is a section taken upon the line 14—14 of Figure 5.

Figure 15 is a plan view of a portion of the strip of tickets.

As shown on the drawings:

The gasoline pump 1 is driven in the usual way by crank 2. The crank operates through a train of gears 3 to work the rack 80 bar 4 by which the piston of the pump is operated. The spindle 5 carrying the last of these gears is prolonged to enter a housing 6 which is an offset from the main housing 7 enclosing the ticket cutting and punching mechanism. The offset housing 6 encloses a pair of gears 8 by which the spindle 5 drives the larger gear 9. The gear 9 is keyed to a shaft 10 and a ratchet clutch member 11 is keyed to the same 90 shaft. A spring 12 between the gear 9 and the clutch member 11 tends to keep this member in contact with a clutch member 13.

The clutch member 13 is provided with 95 ratchet teeth 14 upon the edge thereof and with teeth 15 upon the side face thereof which cooperate with ratchet teeth 16 upon the member 11. A pawl 17 mounted in lugs 18 upon the wall of the housing acts 100 to prevent the clutch member 13 from rotating in one direction, namely, the direction in which the side toward the reader in Figure 5 would move upward. A spring 19 is provided to cooperate with the pawl. Thus when the pump handle 2 is operated in one direction, the gear 9 will rotate idly merely driving the teeth 16 on the clutch

member 11 over the teeth 15 on the clutch member 14. The spring 12 permits the clutch member 11 to move to the right in Figure 5 enough to let the teeth slip.

5 Integral with the clutch member 13 is a sleeve 20 rotatably mounted on the shaft 10. The sleeve 20 carries a pair of sprocket wheels 21. The teeth of these sprocket wheels are adapted to mesh with holes 22 upon the edges of a strip of tickets 23. The strip of tickets is coiled upon a spool 24 supported in stirrup 25 as shown in Figure 1. From this spool the strip is led up over a roller 26 and across the top of the housing 15 7 to a roller 28. From this roller it descends through a slot 29 in the upper edge of the housing 7 and is received between two plates 30 and 31.

Integral with the sleeve 20 is a wheel 36 20 at the left of the left hand sprocket wheel 21. This wheel as illustrated in Figure 11, has a notch 37 in the periphery thereof and dog 38 is provided with a lug 39 adapted to cooperate with the notch. The edge of 25 the lug 39 toward the shaft sleeve 20 is bevelled as shown in Figure 11. The dog 38 is spring pressed towards the wheel 36 by the spring 40 which is curled about the pivot of the dog where the dog is mounted on 30 lugs 41 upon the housing 7. The dog 38 has a second lug 42 adapted to cooperate with a notch 43 in a wheel 44. As shown in dotted lines in Figure 8, the notch 43 is not bevelled at either side so that the lug 35 42 acts to hold the wheel 44 from rotation in either direction. The wheel 44 is integral with a sleeve 45 mounted upon the shaft 10. The wheel 36 has a lug 46 and the wheel 44 has a lug 47 which contact 40 with each other as illustrated in Figure 5 except when the sleeve 20 is rotated by the gear 9.

Besides the wheel 44 upon the sleeve 45 there is another wheel 48 upon the periphery of which there is a lug 49 which has a bevelled edge adapted to coact with the bevelled end of a rock arm 50. This arm is keyed to a shaft 51 mounted in lugs upon the plate 31. At the other end of the shaft 50 51 is a rock arm 52 approximately parallel to the plate 31. The lower end of this arm has a recessed boss 53 in which is pivoted a punching tool 54; holes 56 and 57 in the plates 30 and 31 respectively provide for 55 the motion of the tool. The rock shaft 51 and the rock arms 50 and 52 are biased away from the position in which the punching tool pierces the paper by a spring 58.

The sleeve 45 also carries a ratchet wheel 60 60 which is retained by a pawl 61 pivoted to the side of the housing. The pawl is held against the ratchet wheel by a spring 62. The sleeve 45 extends through the housing 65 and has on the end of it external to the housing a hub 63 for a crank 64.

A notch with bevelled sides is provided at 65 in the side of the wheel 48. A lever 66 pivoted at 67 upon a post 68 has a tail piece 69 the end of which cooperates with the notch 65 and is forced out of this notch 70 when the wheel 48 is rotated. A spring 70 75 presses the tail piece 69 against the wheel 48 and the main arm of the lever 66 toward the bottom of the housing. The end of the lever 66 opposite the tail piece has a tooth shaped end 71. When the tail piece 69 is lifted out of the notch 65 this end 71 will engage between the teeth of the gear 9 and prevent rotation of the handle 2.

The clutch member 13 has upon its face 80 opposite the clutch teeth a cam 72 which operates against the lug 73 upon the short arm 74 of a lever pivoted at 75. The support for this pivot is a bracket 76 secured to the plate 31 near the lower edge thereof. 85 The horizontal part of this bracket has a lug 77 and the short arm 74 has a stud 75^a surrounded by a cushioning of india rubber which contacts with the lug 77 to bring the short arm of the lever gently to rest, in the position illustrated and to produce a tendency of the lever to rebound after the lug is struck. The long arm 78 of the lever has fastened thereto a knife 79. Surrounding the stud upon which this lever is pivoted is a spring 80 by which the knife is moved to cutting position.

Below the knife, the plate 30 is continued as shown at 81, a notch 82 being provided for the reception of the cutting edge of the knife in its extreme position. The plate 81 is paralleled by a plate 83 in the same plane with the plate 31. This plate is fastened to the bottom of the housing as indicated at 84, preferably the outlet 34 of the bottom of the housing is bevelled to meet the lower edges of the plates 81 and 83.

When the device is assembled, the top and bottom portions of the housing are fastened together by a rod 85 which is secured in place by a pad lock 86. Unauthorized tampering with the mechanism is thus prevented.

In the operation of the device the crank 2 is rotated first in one direction and then in the opposite direction, to operate the pump through the rack bar 4. Consequently the spindle 5 and the gear 9 are rotated first in one direction and then in the other. As the gear 9 is rotated in one direction the clutch member 11 slips idly over the clutch member 13 but when the gear 9 is operated in the opposite direction the clutch member 11 drives the clutch member 13 and so drives the sprocket 21. The distance through which these sprockets are moved, depends upon the travel of the pump handle 2 and so upon the amount of gasoline delivered.

When the pump handle 2 comes to rest, 130

due to the pump having come to the end of its stroke, the clutch member 11 will no longer drive the clutch member 13 and the sleeve 20 will come to rest, the sprocket 21 having dragged the strip of tickets a corresponding distance. As illustrated in Figure 15, there is on the tickets a row of numbers to indicate the number of gallons delivered by the pump. The strip 23 will come to rest with the number corresponding to the delivery standing opposite the punching tool. Overrunning of the sleeve 20 and consequent too great travel of the strip is prevented by pressure of the teeth 16 against teeth 15 under influence of the spring 12.

The travel of the sprockets 21 which have produced this motion will be less than a complete revolution. The lug 46 will consequently stand separated from the lug 47. The first motion of the wheel 36 and the sleeve 20 forced the lug 39 out of the notch 37 and so by moving the dog 38 lifted the lug 42 out of the notch 43. This left the sleeve 45 unlocked so that it may now be rotated.

The operator then manipulates the crank 64 and so rotates the sleeve 45. The pawl 61 prevents rotation of the crank 64 in the wrong direction. The first movement of the crank will cause the lug 49 to pass under the end 50 of the rock arm and so rotate the rock shaft 51, Fig. 8. This will rotate the rock arm 52 and drive the tool 54 through the holes 57 and 56 perforating the ticket 43 as indicated at 90 in Figure 15. Further motion of the crank 64 and so of the wheel 48 will cause the notch 91 behind the end 50 of the rock arm to snap over the side of the lug 49 under the influence of the spring 58. This will withdraw the cutting tool 54 from the position in which it traverses the paper.

Still further rotation of the crank 64 will make the lug 47 on the wheel 44 contact with the lug 46 on the wheel 36. As the rotation of the crank 64 is continued the sleeve 20 as well as the sleeve 45 will be rotated thereby. Consequently the sprocket 21 will be rotated and the strip of tickets will again travel downwards. When the rotation is nearly completed, the cam 72 will contact with the stud 73 Fig. 14 and move the lever 78 counterclockwise as shown in Figure 12 and the knife 79 moves away from the paper against the influence of the spring 80.

When the cam 72 gets past the stud 73 the straight edge of the cam will permit the lever 78 to snap under the influence of the spring 80. The knife 79 will pass beyond the position illustrated in Figure 5 so far that the cover cushioning the stud 75 will be compressed against the lug 77. During the moment of this compression, the edge of the knife will be beyond the paper in the

recess 82 at the beginning of the continuation 81 of the plate 30. The elastic force of the rubber cushioning on the stud 75 will return the knife from this extreme position to the position illustrated in Figure 5, in which position it does not prevent travel of the paper.

The ticket which is severed by the knife already has its lower end in the guideway 35, this end of the ticket having passed down between the plates 81 and 83 under the influence of the sprocket 21. When it is severed by the operation of the knife described, the ticket will therefore fall through the guideway 35 and the operator may remove it from the open end 92 of this guideway. The first motion of the crank 64 causes the wheel 48 to move and so lifts the tail 69 of the lever 66 out of the notch 65. This causes the end 71 of the lever 66 to enter between two teeth of the gear wheel 9 and manipulation of the crank 2 is therefore prevented until the operation of punching and delivering a ticket is completed.

When the crank 64 has completed a revolution the spring 40 will cause the dog 38 to move so that the lug 42 enters the notch 43 and the sleeve 45 is locked against further movement. During all of the latter part of the revolution of the crank 64, the lug 47 has been driving the lug 46 and so turning the sleeve 20 against the friction produced by the spring 12 forcing the bevelled teeth of the clutch members 11 and 13 together. Consequently when the crank 64 is brought to a stop by the lug 42 snapping into the notch 43, the lug 46 will stop in a definite place. The next ticket in the strip 23 will therefore be moved to the proper place in the next operation and will in its turn be correctly punched and severed.

The crank 64 cannot again be moved until the crank 2 has been moved so that the wheel 36 has turned and lifted the dog 38. Thus it is not possible to extract a second ticket except on the delivery of a second amount of gasoline. The length of the ticket is made to correspond to a complete revolution of the sleeve 20, and a ticket will be severed by the knife 79 each time that a revolution of the sleeve 20 is completed, the numerals on the ticket being so arranged that the first one is spaced from the end of the ticket by a distance corresponding to the distance between the punch and the severing knife. It is not however necessary that the length of the ticket correspond to a complete up and down stroke of the piston of the pump, even at its maximum capacity, but preferably the ticket is made several times this length so that if the operator desires to deliver upon one ticket a multiple of the maximum capacity of one stroke of the pump, he can

- 1 do so without the necessity of using several tickets. If the operator should deliver more gasoline at one time than corresponds to a complete revolution of the sleeve 20, it 5 would be indicated by the delivery of a ticket which did not have any punch mark. A record of this fact can be obtained by serially numbering the tickets as indicated at 93. If the operator should undertake to de- 10 liver any gasoline without manipulating the crank 64 and so punching the corresponding ticket this fact would be indicated by a skip in the serial numbers of the tickets which the operator would turn in or by the 15 presence of an unpunched ticket which would cause the operator to be charged with the maximum quantity of gasoline called for by the ticket.
- 1 I am aware that numerous details of con- 20 struction can be varied through a wide range without departing from the principles of this invention and I therefore do not purpose limiting the patent granted otherwise than necessitated by the prior art.
- 25 23 I claim as my invention:
1. In a fluid vending machine, the combination with mechanism for delivering a pre-determined quantity of fluid, of means for feeding a strip of tickets, an actuating member and means operated successively by said member for punching and severing a ticket.
  2. A device of the class described, a feed wheel, a gasoline pump, means for rotating said feed wheel a portion of a revolution by the operation of said pump, and means for rotating said feed wheel for the remainder of said revolution independently of the operation of said pump and means limiting said combined movement to one revolution.
  3. A device of the class described, a sprocket, a gasoline pump, means for rotating said sprocket a portion of a revolution by the operation of said pump, and means for rotating said sprocket for the remainder of said revolution independently of the operation of said pump, and means operated by the first movement of the second named means for locking the gasoline pump against further operation.
  4. In a ticket delivering machine, a knife, a cam to operate said knife, a spring for moving said knife against the action of said cam, and a cushioned stop controlling the position of said knife, whereby when the knife moves under the influence of said spring it will go beyond its normal position and be returned to said normal position by the action of said cushioning device.
  5. In a device of the class described, a sprocket and a punch, means controlled by the sprocket for locking the punch from operation, and means controlled by the punch operating means for locking the sprocket driving means from operation.
  6. In a device of the class described, a sprocket, driving means therefor, a punch, means controlled by the sprocket for locking the punch from operation, means controlled by the punch operating means for locking the sprocket driving means from operation, and means integral with the punch operating means for driving the sprocket independently of the action of the first named sprocket driving means.
  7. In a device of the class described, a feed wheel, a crank for driving said feed wheel, a connection between said crank and said feed wheel including a lost motion, and means for adjusting the degree of lost motion in proportion to the quantity of gasoline delivered.
  8. A gasoline delivering mechanism, a sprocket driven thereby, means independent of said gasoline delivering mechanism for additionally driving said sprocket, and a lost motion connection between said last named means and said sprocket, the degree of said lost motion being determined by the movement of the sprocket when driven by the gasoline delivering means.
  9. In combination, two members pivoted upon one shaft, a ratchet upon each of said members and pawls whereby they are required to rotate in the same direction, a lug on each of said members, said lugs co-acting with one another whereby one of said members may move the other in said direction, and means for moving said driven member in said direction independently of said other member, whereby said lugs are separated, said means including a retarding device whereby when said member is driven by the other member the lugs will be prevented from separating.
  10. Two members rotatably mounted upon one shaft, one of said members having a bevelled recess, the other of said members having an unbevelled recess, and a dog provided with lugs to fit in said recesses, said dog being spring pressed into recess engagement position, whereby motion of the first of said members must be made before the other of said members can be moved, said first member and recess therein being adapted when moved to raise said dog to release said second member.
  11. In combination, a ticket punching means and a ticket severing means, a strip of tickets, a guideway, means for moving said strip through said guideway, each of the tickets in said strip having a series of numerals, said series being parallel to the length of the strip and positioned to be designated by the punchmarks, the distance of the first of said numerals from the end of said ticket corresponding to the distance between the punching mechanism and said ticket severing mechanism.
  12. In a device of the class described, a gasoline delivery mechanism, a ticket posi-

- tioning mechanism, a ticket punching mechanism, a shaft rotated by said gasoline delivery mechanism, a sleeve on said shaft driven by the rotation thereof to operate the ticket positioning mechanism, a second sleeve on said shaft rotated independently of said gasoline delivery mechanism, two cams upon said second sleeve, means operated by one of said cams for locking said gasoline delivery mechanism, and means operated by the other of said cams for operating the ticket punching mechanism.
13. In a device of the class described, gasoline delivery mechanism, a shaft, a sleeve on said shaft, means operated by the gasoline delivery mechanism for rotating said sleeve, a second sleeve on said shaft, means for locking said second sleeve against rotation, a cam on said first sleeve for moving said locking means to unlock position, two cams on said second sleeve, means operated by one of said cams for locking the gasoline delivery mechanism, a ticket punching mechanism, means operated by the second of said cams for operating the ticket punching mechanism, a ticket delivery mechanism operated by said first sleeve, and means operated by said second sleeve for rotating said first sleeve beyond the point to which it was rotated by the gasoline delivery mechanism.
14. In a device of the class described, gasoline delivery mechanism, a ticket positioning mechanism, a ticket punching mechanism, a shaft rotated by said gasoline delivery mechanism, a sleeve on said shaft, driven by the rotation thereof to operate the ticket positioning mechanism, a second sleeve on said shaft rotated independently of said gasoline delivery mechanism, two cams upon said second sleeve, means operated by one of said cams for locking said gasoline delivery mechanism, and means operated by the other of said cams for operating the ticket punching mechanism, a ticket severing mechanism, a cam on said first sleeve, and means actuated by said cam for operating the ticket severing mechanism.
15. A gasoline delivery mechanism, a shaft rotated thereby, a sleeve on said shaft, a clutch member keyed to said shaft, a clutch member integral with said sleeve, coacting ratchet teeth upon the adjacent faces of said clutch members, a spring pressing one of said clutch members toward the other, a pawl and ratchet permitting movement of said sleeve in one direction whereby actuation of the gasoline delivery mechanism will operate said shaft to drive said sleeve in the direction permitted by said pawl and ratchet, and means independent of the gasoline actuated mechanism for rotating said sleeve whereby upon said last named rotation the teeth of said clutch members will slip over one another afford-
- ing friction so that this sleeve will not go further than it is driven by said second driving mechanism.
16. In a ticket punching and delivering mechanism, a housing, two plates mounted within said housing constituting a guideway for said ticket, ticket punching mechanism, ticket severing mechanism, a lever for operating one of said mechanisms, and a lever for operating the other of said mechanisms, both of said levers mounted upon the same one of said plates.
17. In a ticket punching and delivering mechanism, a housing, two plates mounted within said housing constituting a guideway for said ticket, ticket punching mechanism, a lever for operating one of said mechanisms, a lever for operating the other of said mechanisms, both of said levers mounted upon the same one of said plates, and a supplemental plate adjacent to the ticket severing mechanism forming a continuation of said guideway whereby said tickets are positively guided throughout the whole of said housing.
18. In a vending machine, a supply roll, a strip of paper delivered from said roll, two plates between which said strip is guided, said plates having a pair of aligned holes, one in each plate, a punch reciprocating in said holes, means for moving the strip between said holes past said punch a distance corresponding to the quantity of material delivered by said machine, and means for reciprocating said punch after said movement of the strip is completed.
19. In a vending machine, means for delivering a controlled quantity of merchandise, a strip of tickets, means for making a record on said strip, and means for moving the strip past said record making means a distance proportional to the quantity of merchandise delivered, means for thereafter moving said strip a sufficient distance to make its total travel an integral number of tickets and means for severing the record bearing portion of the strip after said two movements of said strip, each of said means being automatically controlled by the operation of said merchandise delivery mechanism.
20. In a fluid vending machine, the combination with mechanism for delivering a predetermined quantity of fluid, ticket feeding mechanism operated by said delivery mechanism, a ticket punching mechanism, a ticket severing mechanism, an actuating member for said punching and severing mechanism, said punching and severing mechanisms bearing a definite angular relation with said actuating member and with each other.
21. In a machine for delivering merchandise and tickets, means for recording the delivery of the merchandise on the ticket,

100

105

110

115

120

125

130

means for positioning the ticket relative to the recording means in accordance with the quantity of merchandise delivered, means for actuating the recording means and delivering the ticket, and interlocking means whereby said actuating and ticket delivering means are held from operation during the action of said ticket positioning means.

22. The combination with a measuring pump, of a member movable back and forth by and proportionately with the pump piston, ticket feeding means operable on movement of said member in one direction to move the ticket by distances equal to various fractions of its length depending on the stroke of the pump piston, and auxiliary feeding means subsequently operable to move the ticket by complementary distances.

23. The combination with a measuring pump, of a member movable back and forth by and proportionately with the pump piston, strip feeding mechanism operable on each cycle of movement of said member to move the strip a predetermined distance and including a primary feeding means effective on movement of said member in one direction to move the strip by various distances not exceeding said predetermined distance and a secondary feeding means effective to move the strip the remainder of said predetermined distance.

24. The combination with a measuring pump, of a member movable back and forth by and proportionately with the pump piston, ticket feeding means operable on movement of said member in one direction to move the ticket by distances equal to various fractions of its length depending on the stroke of the pump piston, auxiliary feeding means subsequently operable to move the ticket by complementary distances, and means operable after the operation of the first named feeding means and before operation of the last named feeding means to mark the ticket to indicate the quantity of liquid dispensed from the pump.

25. The combination with a measuring pump, of a member movable back and forth by and proportionately with the pump piston, ticket feeding means operable on movement of said member in one direction to move the ticket by distances equal to various fractions of its length depending on the stroke of the pump piston, auxiliary feed-

ing means subsequently operable to move the ticket by complementary distances, and means operable to mark the ticket to indicate the quantity of liquid dispensed from the pump.

26. In combination with a dispensing pump, ticket marking means, mechanism operable by movement of the pump piston on its delivery stroke to move the ticket relatively to said means by a distance proportionate to the distance travelled by the pump piston, said mechanism being ineffective to move the ticket on the return stroke of the piston, means operable to mark the ticket at the location to which it is moved by said mechanism and means operable to move the ticket the remainder of its length.

27. In combination, ticket marking means, mechanism to move a ticket to any of various predetermined positions with relation to said means, means operable after the operation of said mechanism to actuate the first named means, and mechanism operable thereafter to move the ticket the remainder of its length.

28. In combination, an operating member movable back and forth and having a variable stroke, strip marking means, a record strip having its leading end substantially in line with said means, primary and secondary strip feeding mechanism operable alternately and together effective to move the strip a constant distance on each cycle of operation of said member, said primary mechanism effective on one stroke only of said member and moving the strip a distance proportionate to the stroke of said member, said secondary mechanism moving the strip the balance of said constant distance, and means operable between the operations of the primary and secondary mechanisms to actuate said marking means.

29. In a fluid vending machine, the combination with mechanism for delivering a predetermined quantity of fluid, ticket feeding mechanism operated by said delivery mechanism, a ticket punching mechanism and a ticket severing mechanism operable successively by the same rotation of an actuating member.

In testimony whereof I have hereunto subscribed my name.

CLARENCE A. ROSS.
